BY
John Shinn,
ATTORNEY.

UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 29,164, dated August 2, 1898.

Application filed June 16, 1898. Serial No. 683,649. Term of patent 3½ years.

To all whom it may concern:

Be it known that I, WILLIAM T. SMITH, a citizen of the United States, residing at Philadelphia, in the county of Philadelphia and State of Pennsylvania, have invented and produced 5 a new and original Design for a Woven Fabric, of which the following is a specification, reference being had to the accompanying drawing, making a part of the same.

10 The leading features of my design are clearly shown in the drawing, which represents a battle-ship, and below a small panel, off the bow, are represented a lighthouse and fort. From the fort is shown the representation of

an electric cable connecting a mine placed 15 under the bow of the battle-ship. At each of the lower corners is the representation of an American shield, the whole surrounded by a chain-link border, as shown.

Having, as above, fully described my invention, what I claim as new, and desire to secure by Letters Patent, is—

The design for a woven fabric, as shown and described.

W. T. SMITH.
